UNITED STATES PATENT OFFICE.

CLINTON F. BLAKE, OF PORTLAND, OREGON, ASSIGNOR TO WILLIAM F. ROGERS, OF PORTLAND, OREGON.

DIFFUSING APPARATUS.

1,144,525.

Specification of Letters Patent. Patented June 29, 1915.

Application filed December 9, 1913. Serial No. 805,618.

To all whom it may concern:

Be it known that I, CLINTON F. BLAKE, a citizen of the United States, residing at Portland, in the county of Multnomah and 5 State of Oregon, have invented certain new and useful Improvements in Diffusing Apparatus, of which the following is a specification.

My invention relates to an apparatus for 10 diffusing a measured amount of any liquid from one vessel into any liquid contained in another vessel, or more particularly to disinfectant apparatus for toilets and the like wherein a measured amount of the liquid 15 disinfectant is to be discharged into the flush water upon each operation of the toilet for purposes to be hereinafter fully explained.

The object of my invention is to provide a 20 device of this kind that is simple in construction, durable, efficient in operation, and inexpensive in manufacture.

With these and other useful objects in view, the invention consists of certain novel 25 features of construction, combinations of elements, and arrangement of parts to be fully set forth and specifically claimed hereinafter.

In order to clearly comprehend my invention 30 and the art to which it relates, reference is made to the accompanying drawings which form part of this application, of which:—

Figure 1 is a longitudinal section of my 35 invention taken on line A A, Fig. 2, and of a tank to which it is attached; Fig. 2 is a plan view of same with said tank removed; Figs. 3 and 4 are similar views to Fig. 1, showing different positions of the liquids, 40 and Fig. 5 is a modification of my invention, showing how it may be connected to a plurality of tanks.

In the several figures of the drawings in 45 which like characters of reference indicate like parts, the numeral 2 indicates a container which is integral with chamber 3, siphon-pipe 4, and air-pipe 5; a small aperture 6 passes through bottom 7 of container 2, and opens into chamber 3, for 50 purposes to be hereinafter fully explained.

Container 2 has also attached therein a tube 8 that passes through the bottom 7, of said container to which said tube is fixed, to a plane level with end 9 of siphon-pipe 4.

55 When said container 2 is filled through

opening 10, screw-cap 11 is placed therein and the container rendered air-tight. After said cap is screwed into said opening, the container is inverted as shown in the drawings, placed into tank 12 as illustrated 60 which may be the flush tank of the toilet, and fixed thereto by any practical or convenient means.

After said container is filled and attached to the tank as aforesaid, the liquid in said 65 container drops downwardly through aperture 6 into chamber 3 until it reaches the level of end 9^a of pipe 8, which it then seals and thus prevents the flow of air from aperture 5^a into pipe 8.

70 As pipe 8 provides the only communication of container 2 with the atmosphere (through chamber 3 and pipe 5) when said pipe 8 is thus sealed at its lower end no air can find admittance into container 2 and 75 thus no further liquid will be discharged through aperture 6.

In order to operate the invention, the level of the water in tank 12 is raised to a line indicated by arbitrary line 12^a to height 80 above top 4^b of siphon-pipe 4.

The liquid contained in tank 12, enters 85 chamber 3 through aperture 4^a of siphon-pipe 4, mixing with the liquid formerly contained in said chamber 3, and thereby diffuses said liquid throughout the chamber, from which it passes by reason of the lowering of the level of the liquid in tank 12, to arbitrary line 12^b, as shown in Fig. 4, to a 90 level below point 4^c of siphon-pipe 4, thereby causing a siphon action in aperture 4^a, which action continues until the liquid in chamber 3 is emptied into tank 12 and the two liquids are completely mixed. The 95 foregoing operations may be repeated an indefinite number of times for the purposes aforesaid.

My invention may be constructed of any material and made any size deemed suitable for all the requirements of such an apparatus, and while I have illustrated and described a preferred form of mechanism and combinations of elements considered essential in materializing the same, I wish to include in this application all mechanical 100 equivalents and substitutes that may be fairly considered to lie within the scope and purview of my invention as defined in the appended claim.

105 Having thus fully described my invention 110

so that others skilled in the art to which it appertains may be enabled to construct and use the same, what I claim and desire to secure by Letters Patent, is—

5 In a diffusing device for handling liquid disinfectant, a container adapted to contain liquid disinfectant and having a discharge orifice in the bottom thereof, a receiving chamber below said container adapted to receive the liquid disinfectant as same is discharged from the container through said orifice, an air tube connecting said container and said receiving chamber, said air tube terminating adjacent to the top of 10 said container and adjacent to the bottom of said receiving chamber, said container being tightly closed except for said air

15 Copies of this patent may be obtained for five cents each, by addressing the "Commissioner of Patents, Washington, D. C."

tube and said discharge orifice, and said discharge orifice being of such size that liquid will pass therethrough when air is admitted to said container through said air tube, but that the liquid will not run out of said discharge orifice when said air tube is closed, an air tube connecting said receiving chamber with the atmosphere, and a siphon discharge connected to said receiving chamber.

In testimony whereof I hereunto affix my signature in the presence of two witnesses.

CLINTON F. BLAKE.
